UNITED STATES PATENT OFFICE.

LESTER FERENCI, OF BROOKLYN, NEW YORK, ASSIGNOR TO INTERNATIONAL CIGAR MACHINERY COMPANY, A CORPORATION OF NEW JERSEY.

BUNCH TRANSFER FOR CIGAR MACHINES.

Application filed April 21, 1928. Serial No. 271,877.

This invention relates to bunch transfers for cigar machines, for taking out the cigar bunches from the various mechanisms of a cigar machine and depositing them into other mechanisms, its main object being to improve the operation of the bunch grippers.

Hitherto in transfers the bunch grippers started opening before the bunch reached the point at which it was to be deposited, thus resulting in dropping the bunch if unusually small. It is an object of the invention to make gripping mechanism in which the opening of the grippers will take place during the first part of the return movement of the transfer arm.

In transfers hitherto employed the operation of the grippers was effected by spring pressure, so that the pressure on the bunch would vary on large and small bunches, thus resulting in dropping of a small bunch or sticking fast of a large bunch when the spring pressure was set for a given sized bunch. It is an object of the present device to provide a gripper mechanism which will produce uniform gripping pressure, despite variations in the size of the bunch, and to eliminate springs from the means actually pressing the grippers against the bunch.

Another object of the invention is to provide a gripper operating mechanism which will operate quickly with respect to the movement of the transfer arm, so that there will be a little movement of the transfer arm during the opening or closing movement of the grippers.

With these and other objects not specifically mentioned in view, the invention consists of certain constructions and combinations which will be hereinafter more fully described and then specifically set forth in the appended claims.

Generally speaking, the present device includes fixed and pivoted grippers mounted on an oscillating transfer arm, the pivoted gripper being provided with a pinion gear in engagement with a frictionally retarded gear segment. The frictionally retarded gear segment on movement of the arm tends to rotate the pivoted gripper to closed or open position, depending on the direction of movement of the arm. When the gripper has been rotated to its open or closed position, the pinion causes the segmental gear, which is pivoted on the same axis as the arm, to follow the motion of the arm, all

the time tending to cause rotation of the pinion and further pressure on the pivoted gripper.

In the accompanying drawings:

Fig. 1 is a front elevation of the improved cigar bunch transfer, arranged for holding the bunch crosswise with respect to the path of movement thereof;

Fig. 2 is a side elevation, partly in cross-section, of the crosswise transfer shown in Fig. 1;

Fig. 3 is a side elevation, partly in cross-section, of a gripper mechanism modification for the improved bunch transfer, arranged for holding the bunch lengthwise of the path of movement; and

Fig. 4 is a sectional plan view of the gripper mechanism of the lengthwise bunch transfer, taken on line 4-4 of Fig. 3.

In carrying the invention into effect, there is provided a transfer arm mounted for oscillation, bunch grippers carried by said arm, means for oscillating said arm to cause said grippers to transport a bunch, and mechanism brought into action by the first part of the movement of said arm in each direction for operating said grippers. In the best constructions contemplated, the said operating means includes a friction actuating device for operating the grippers. In the best constructions also, this operating means includes a friction controlled shaft and means connecting said shaft with one of said grippers. The means above referred to may be widely varied in construction within the scope of the claims, for the particular machine selected to illustrate the invention is but one of many possible embodiments of the same. The invention therefore is not to be restricted to the precise details of the structure shown and described.

Referring to Figs. 1 and 2, a swinging transfer arm 5 is clamped on a sleeve shaft 6 having integral therewith gear 7, which is oscillated by a rack 8 operated from the cigar machine. The sleeve shaft 6 is journaled in a support 9 and supports within it a pivot shaft 10. The swinging arm 5 has journaled on its free end a shaft 11, to which is adjustably clamped a sprocket 12 connected with a stationary sprocket 13 of equal size, by a chain 14 provided with a chain tightener spring 15. Near the forward end of the shaft 11, which is held in place by a fixed collar 16, is clamped in pendent posi-

tion a stationary gripper 17 which co-operates with movable gripper 18 loosely pivoted on the shaft 11 on both sides of the clamp portion of the stationary gripper. These 5 grippers carry the cigar bunch B in horizontal position, hanging below the shaft 11. The stationary sprocket 13 is loosely centered on the sleeve shaft 6 and is fastened to the support 9 by a pin 19, so that the oscillating 10 motion of the transfer arm 5 turns the sprocket 12 by the exact amount required to keep the grippers in a vertically pendent position at any point during its swing.

The movable gripper 18 is clamped to the 15 hub of a gear wheel 20, which is loosely mounted on shaft 11 carried by the transfer arm. The gear 20 is in mesh with a gear segment 21, which is fixedly mounted on the front end of the pivot shaft 10, while the rear 20 end of that shaft is held by friction against a stationary bracket 22 attached to the pedestal 9. The rear end of the shaft 10 is threaded and has on it an adjusting nut 23, by which a coil spring 24 is forced against a 25 slide friction collar 25, which is kept from turning with respect to shaft 25 by a pin 26 in the shaft projecting into a slot in the collar and which presses friction washers 27 between a shoulder 28 of the shaft 10, the collar 25, and 30 the bracket 22 thereby clamping the shaft to the bracket, the free end of which forms a collar between the friction washers. The movable gripper 18 carries a stop pin 29 which 35 engages a lug 30 of the stationary finger 17 when the movable finger is opened to discharge a bunch. To accurately locate the end positions of the arm 5, the adjustable stop screws 31 are provided in the same, which engage a stop pin 32 attached to support 9.

40 In the operation of the device, when the transfer arm is in position to grip the bunch to be transferred, the first part of the transfer movement causes the gear 20 to be rotated by the frictionally held gear segment 21, thus 45 swinging the pivoted gripper 18 to gripping position, as shown in dotted lines on the left hand of Fig. 1. Further movement of the transfer arm causes the now relatively stationary gear 20 to carry the gear segment 21 50 along with the arm 5. During the remainder of the transfer movement, however, the frictional retarding of the gear segment by the frictional means 27 and 28 acting on the stationary bracket 22, constantly tends to rotate the pivoted gripper 18 to closed position, thus maintaining a uniform pressure on the 55 cigar bunch which is independent of the size of the bunch. After the transfer arm has carried the bunch to the position at which it is 60 to be deposited and has started back, the pivoted gripper 18 is again free to rotate. The tendency of the frictionally held gear segment is now to rotate the gear 20, and with it the gripper 18, to open position. Consequently, the return movement of the arm 5

causes the gear 20 to roll along the gear sector 21, opening the pivoted gripper 18 and releasing the bunch. The gripper 18 opens until the stop pin 29 on said gripper engages the lug 30 of the stationary gripper. The 70 gear 20 is then again locked against rotation and carries the gear sector 21 along with the transfer arm 5 as before.

Referring to Figs. 3 and 4, in which a modified form of the device for lengthwise transfer of a bunch is shown, the movable gripper 18^a, which in this form is secured on the cross pin 33, is supported for rotation in the head block 34 fast on the shaft 11^a. This gripper is actuated by a bevel gear segment 35 75 and clamped on the hub of a gear wheel 20^a and meshing with the bevel gear segment 36 attached to the cross pin 33. This bevel gear segment 36 on movement of the bevel gear segment 35, in response to the action of gear segment 21 on gear 20^a, will move the gripper 18^a exactly as the gripper 18 in the above described form. The stationary gripper 17^a is fastened to the head block 34 and has a lateral projection 37 which takes the place of the lug 90 30 of the cross wise transfer, limiting the opening movement of the gripper 18^a by engagement with the lug 38 on the gripper 17^a. All other parts of the lengthwise transfer are identical with the respective parts of the crosswise transfer hereinbefore described and, therefore, no further description thereof is deemed necessary.

It will be seen from the above descriptions 100 that the radius of the gear segment 21 being relatively large compared with that of the gear 20, the closing movement of the gripper 18 will be relatively quick with respect to the movement of the transfer arm. Indeed, by changing the relative radii of these two parts, 105 the closing movement of the gripper 18 may be made as near instantaneous as practically desirable.

By adjusting the thumb screw 23, the pressure exerted by the grippers on the bunch may 110 be readily adjusted as desired. It is noted in this connection that the only spring used in this improved mechanism is the one employed to adjust the friction of the pivots and since this spring is under hand control, 115 its constancy is immaterial to the reliability of the device. This is of importance because springs vary with use and, therefore, elimination of springs eliminates a source of 120 variation in pressure of the grippers on the bunch.

What is claimed is:

1. In a cigar bunch transfer, the combination with an arm, of bunch grippers carried by said arm, means for oscillating said arm to cause said grippers to transport a bunch, and mechanism brought into action by the first part of the movement of said arm in each direction for operating said grippers. 125
2. In a cigar bunch transfer, the combina- 130

- tion with an arm, of bunch grippers carried by said arm, means for oscillating said arm to cause said grippers to transport a bunch, and mechanism brought into action by the 5 first part of the movement of said arm in each direction for operating said grippers, said arm having means for maintaining the grippers in pendent position during arm oscillation.
- 10 3. In a cigar bunch transfer, the combination with an arm, of bunch grippers carried by said arm, means for oscillating said arm to cause said grippers to transport a bunch, and mechanism brought into action by the 15 first part of the movement of said arm in each direction for operating said grippers, said arm having sprockets and a chain for maintaining the grippers in pendent position during arm oscillation.
- 20 4. In a cigar bunch transfer, the combination with an arm, of bunch grippers carried by said arm, means for oscillating said arm to cause said grippers to transport a bunch, and mechanism brought into action by the 25 first part of the movement of said arm in each direction for operating said grippers, said grippers including one which is moved with respect to the other by said operating means.
- 30 5. In a cigar bunch transfer, the combination with an arm, of bunch grippers carried by said arm, means for oscillating said arm to cause said grippers to transport a bunch, and mechanism brought into action by the 35 first part of the movement of said arm in each direction for operating said grippers, said oscillating means including a pinion for moving said arm and a rack for moving said pinion.
- 40 6. In a cigar bunch transfer, the combination with an arm, of bunch grippers carried by said arm, means for oscillating said arm to cause said grippers to transport a bunch, and mechanism brought into action by the 45 first part of the movement of said arm in each direction for operating said grippers, said
- operating means including a friction actuating device.
7. In a cigar bunch transfer, the combination with an arm, of bunch grippers carried by said arm, means for oscillating said arm to cause said grippers to transport a bunch, and mechanism brought into action by the 50 first part of the movement of said arm in each direction for operating said grippers, said operating means including a friction controlled shaft and means connecting said shaft with one of said grippers.
8. In a cigar bunch transfer, the combination with an arm, of bunch grippers carried by said arm, means for oscillating said arm to cause said grippers to transport a bunch, and mechanism brought into action by the 55 first part of the movement of said arm in each direction for operating said grippers, said operating means including a friction controlled shaft at the pivotal axis of said arm, a gear sector carried by said shaft, and a pinion meshing with said sector and connected with one of said grippers.
9. The combination with a support, of a pinion sleeve journaled in said support, a reciprocating rack oscillating said pinion sleeve, an arm carried by said sleeve, cigar bunch grippers carried by said arm, a shaft 70 within said sleeve, a friction device resisting movement of said shaft, and gripper operating connections actuated by said shaft during the first part of each rack stroke.
10. The combination with a support, of a pinion sleeve journaled in said support, a reciprocating rack oscillating said pinion sleeve, an arm carried by said sleeve, cigar bunch grippers carried by said arm, a shaft 75 within said sleeve, a friction device resisting movement of said shaft, a gear sector carried by said shaft, and a pinion meshing with said sector and connected with one of said grippers.
- In testimony whereof, I have signed my 90 name to this specification.

LESTER FERENCI.
